UNITED STATES PATENT OFFICE.

FRANZ WEBEL, OF MANNHEIM, GERMANY, ASSIGNOR TO BADISCHE ANILIN & SODA FABRIK, OF LUDWIGSHAFEN-ON-THE-RHINE, GERMANY, A CORPORATION.

PRODUCING ISOPRENE.

1,098,859.

Specification of Letters Patent. Patented June 2, 1914.

No Drawing.

Application filed February 27, 1913. Serial No. 751,106.

To all whom it may concern:

Be it known that I, FRANZ WEBEL, citizen of the German Empire, residing at Mannheim, Germany, have invented new and useful Improvements in Producing Isoprene, of which the following is a specification.

I have found that I can obtain isoprene by treating methyl-butenol esters at a raised temperature and in the vaporized state with a reagent which will catalytically split off acid, such for instance as alumina, which is particularly useful, and also barium chlorid and nickel chlorid. It is advantageous to carry out the reaction under reduced pressure.

Methyl butenol esters suitable for employment according to this invention can be obtained by reacting with a salt of an organic acid on dimethyl-monohalogen-ethyl-halogen-methane as described in the application for patent Serial No. 751,105.

The following example will serve to illustrate further the nature of this invention and how it can be carried into practical effect, but my invention is not confined to this example. Pass vaporized methyl-butenol acetate (for instance the crude product obtainable from trimethyl-ethylene bromid and sodium acetate according to Example 1 of the specification of application for patent Serial No. 751,105) over alumina at a temperature of 400° C. and a pressure of about 60 millimeters. Pass the vapors leaving the contact space through a condenser, in which the main quantity of the acetic acid produced is condensed, then through a wash-bottle containing alkaline liquor in order to free the gas completely from acid, and then condense the isoprene vapors in apparatus cooled to, say —80° C. In this way a good yield of very pure isoprene is obtained.

If desired, the process may be carried out

under atmospheric pressure, although the yield is then generally not quite so good. Further, instead of methyl-butenol-acetate, 45 other esters can be employed, in particular other fatty acid esters of methyl-butenol.

The temperature at which the process of my invention can be carried out may be varied within wide limits. 50

Now what I claim is:—

1. The process of producing isoprene by treating a methyl-butenol ester at a raised temperature and in the vaporized state with a reagent which will catalytically split off 55 acid.

2. The process of producing isoprene by treating a methyl-butenol ester at a raised temperature and in the vaporized state with a reagent which will catalytically split off 60 acid, while employing reduced pressure.

3. The process of producing isoprene by treating a methyl-butenol ester at a raised temperature and in the vaporized state with alumina. 65

4. The process of producing isoprene by treating a methyl-butenol ester at a raised temperature and in the vaporized state with alumina, while employing reduced pressure.

5. The process of producing isoprene by 70 treating methyl-butenol acetate at a raised temperature and in the vaporized state with alumina.

6. The process of producing isoprene by treating methyl-butenol acetate at a raised 75 temperature and in the vaporized state with alumina, while employing reduced pressure.

In testimony whereof I have hereunto set my hand in the presence of two subscribing witnesses.

FRANZ WEBEL.

Witnesses:

JOSEPH HEIFFER,
J. ALEC. LLOYD.
